LET-OFF MECHANISM

Leonard M. Rogers, Mendon, Mass., assignor to
 Draper Corporation, Hopedale, Mass., a corpora-
 tion of Maine

Application December 14, 1936, Serial No. 115,743

5 Claims. (Cl. 139—100)

The present invention pertains to let-off mechanisms for looms, and has more particular reference to the supporting means for supporting the warp beam in proper relation to the let-off shaft of such mechanisms.

In mechanisms of the type to which my invention pertains, a warp beam is rotatably mounted in warp beam bearings and a let-off shaft is supported by a loom side and geared to the warp beam for controlling the rate of rotation of the latter. Looms are commonly constructed with identical loom sides and let-off shafts but with warp beams of various different diameters. It is also common practice for mills having looms with warp beams of a given diameter to change the looms to accommodate warp beams of a different diameter. The construction of most looms is such that a warp beam of a relatively large diameter is positioned farther rearwardly in the loom than is a warp beam of a smaller diameter.

Prior to the present invention, such looms, as commonly constructed, included warp beam bearings fixed to the loom sides and adapted to support a warp beam in only one predetermined position. This prior construction requires that the manufacturer provide a number of different designs of warp beam bearings, and also that a mill purchase new bearings whenever larger or smaller warp beams are to be installed. It has been proposed to obviate these disadvantages by constructing the warp beam bearings with a plurality of journal-receiving pockets for supporting a warp beam in any of a plurality of positions. Another prior proposal was to form the warp beam bearing on the upper end of a bracket which was adjustable up and down and forwardly and rearwardly on a stand projecting rearwardly from the loom side. These prior proposed constructions were too expensive, and were otherwise impractical, and they have not been used commercially.

It is a principal object of the present invention to provide, in a loom having a warp beam and let-off shaft geared to the warp beam as aforesaid, a loom side having an arcuate portion the center of which coincides with the axis of the let-off shaft, and a warp beam bearing supported on the arcuate portion and adjustable along the same, whereby the warp beam bearing may be adjusted about the axis of the let-off to proper position to accommodate any of the usual sizes of warp beam.

The foregoing and other objects of the invention are accomplished in the construction illus-

trated on the accompanying drawing, of which:

Fig. 1 is a view in side elevation of a portion of a loom having the preferred embodiment of my invention applied thereto;

Fig. 2 is a rear view of a portion of the warp beam bearing and loom side shown on Fig. 1; and

Fig. 3 is a plan view of the same.

The loom shown on the drawing includes loom sides, such as loom side 1, which may be of any conventional construction except that they are provided with an arcuate portion as hereinafter described in detail. A conventional warp beam 2 has journals 3 by which it is rotatably supported at the rear of the loom. The warp sheet 15 W unwinds from the warp beam and passes over a whip roll 4 and thence to the conventional weaving instrumentalities, not shown. The rate of advance of the warp sheet is controlled by suitable let-off controlling means such as that indicated generally at 5. The let-off mechanism includes a let-off shaft 6 which is geared to the warp beam and revolves under control of the let-off controlling means 5.

The let-off shaft 6 is supported for rotation in a bearing 7 which is fixed to the loom side 1 in any suitable manner, not shown. The position of the let-off shaft in the loom being fixed, it is desirable that the various warp beam positions be located along an arc of a circle the center of which is at the axis of the let-off shaft. With such a construction, warp beams of a relatively large diameter will be positioned downwardly as well as rearwardly from the position of a relatively smaller diameter warp beam, the respective gears 8 on the warp beam being alike in each instance and remaining in proper operative relation to the let-off shaft.

In accordance with the present invention, the loom side 1 is provided with an arcuate portion 9 the center of which coincides with the axis of the let-off shaft 6, and a warp beam bearing 10 is supported by this arcuate portion and adjustable therewith to adjust the position of the warp beam about the axis of the let-off shaft. It will be understood that a similar arcuate support and warp beam bearing are provided at the other side of the loom.

In the particular embodiment shown on the drawing, the arcuate portion 9 is in the form of a flange formed integrally with the loom side and of substantially the same width as the strengthening web 11 commonly provided on loom sides. This flange preferably extends from a point directly above the let-off shaft 6 rearwardly and

downwardly in arcuate form. The external surface of the flange 9 is provided with a series of pockets 12 which are spaced apart along the circumference of the flange. These pockets, as shown, may be in the form of grooves or depressions extending across the flange transverse to the plane of the loom side. The inner side face 13 of the loom side is preferably flat.

The outer face of warp beam bearing 10 contacts the inner face 13 of the loom side, but the bearing projects above and to the rear of the arcuate flange 9. This outer face of the bearing 10 is provided with integral lugs 14 and 15 which project into two of the pockets 12. The spacing 15 of the pockets 12 and lugs 14 and 15 is such that the bearing 10 may be moved along the flange 9 and the lugs selectively positioned in any of the several different pockets. These lugs are shaped to fit snugly into the pockets whereby the warp beam bearing is firmly supported in any of several positions.

The main body of the warp beam bearing is provided with a single bearing surface 16 for receiving the journal 3 of the warp beam. The 25 journal 3 may be held in the bearing by a beam lock 17 which is pivoted to the bearing at 18 and releasably locked to an upright standard on the bearing by suitable locking means 19. This beam lock is not of the present invention, it being disclosed and claimed in patent to C. D. Brown, No. 1,765,322, granted June 17, 1930 and to which patent reference may be had for a more complete disclosure.

The warp beam bearing 10 is adapted to be 35 clamped to the loom side in any of the several positions to which it may be adjusted. To this end, the loom side may be provided with a series of holes 20, 20 to receive bolts 21, 21 which pass through the loom side and warp beam bearing.

40 It will be seen that I have thus provided a construction wherein a single warp beam bearing may be supported on a loom side in any of a plurality of positions, to thereby accommodate any of the customary sizes of warp beam. Furthermore, this desirable result is accomplished in a 45 simple and inexpensive construction, which construction may be adapted to utilize any good, substantial form of beam lock. The invention is not, however, limited to the particular embodiment 50 shown and described.

Having fully disclosed the preferred embodiment of my invention, I claim:

1. In a loom, a warp beam, a let-off shaft 55 geared to said warp beam, a loom side supporting said let-off shaft, said loom side having an integral arcuate flange the center of which coincides with the axis of said let-off shaft, a warp beam bearing including a bearing surface in which said warp beam is journalled and a beam 60 lock releasably locked to the main body of the bearing, said bearing engaging and supported by said flange, said bearing and warp beam being

adjustable along said flange about the axis of said let-off shaft, and means for securing said bearing to said loom side in any of a plurality of positions along said flange.

2. In a loom, a warp beam, a let-off shaft 5 geared to said warp beam, a loom side supporting said let-off shaft, said loom side having an integral arcuate portion the center of which coincides with the axis of said let-off shaft, a warp beam bearing in which said warp beam is journaled, said bearing comprising a main body engaging and supported on said arcuate portion and adjustable therewith to adjust the warp beam about the axis of said let-off shaft and a beam lock releasably locked to said main body, and 15 means for clamping said bearing to said loom side in any of a plurality of adjusted positions.

3. In a loom, a warp beam, a let-off shaft 20 geared to said warp beam, a loom side supporting said let-off shaft, said loom side having an integral arcuate flange the center of which coincides with the axis of said let-off shaft, said flange having a series of pockets spaced along the circumference thereof, a warp beam bearing in which said warp beam is journaled, said bearing having integral supporting lugs adapted to be selectively positioned in any of different pockets of said series for adjusting the position of the bearing and warp beam about the axis of said let-off shaft, and means for clamping said bearing to said loom side with said lugs supported in any of said different pockets. 25

4. In a loom, the combination of a loom side 30 having a let-off shaft bearing and an arcuate portion the center of which coincides with the axis 35 of said bearing, a warp beam bearing having lugs projecting from one side face thereof and resting on said arcuate portion with said side face in contact with one side face of said loom side, said yarn beam bearing being adjustable to any of 40 a plurality of circumferentially spaced positions on said arcuate portion, and means for clamping said yarn beam bearing to said side face of said loom side in any of said positions. 45

5. In a loom, the combination of a loom side 45 having a let-off shaft bearing and an integral arcuate flange the center of which coincides with the axis of said bearing, said flange having a series of circumferentially spaced pockets formed therein, a warp beam bearing having a plurality 50 of lugs projecting from one side face thereof and adapted to be supported in any of a plurality of different pockets in said series, whereby said warp beam bearing is adjustable about the axis of said let-off shaft bearing and is supported by 55 said flange in any of a plurality of adjusted positions, said side face of said warp beam bearing being in contact with the loom side, and means for clamping said warp beam bearing to the loom side with the bearing in any of said adjusted 60 positions. 65
